CLAIM

The ornamental design for foldable front cover for electronic device, as shown and described.

DESCRIPTION

FIG. 1 is a front perspective view of a first embodiment of a foldable cover for electronic device in accordance with our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIGS. 8 and 9 are perspective views of the cover folded into a stand for supporting an electronic device.

The broken lines represent portions of the structure that forms no part of the claim.
